DEHORNING CHISEL

Alphons M. Kuhl, Omaha, Nebr.

Substituted for abandoned application Serial No.
443,428, May 18, 1942. This application August
13, 1943, Serial No. 498,480

12 Claims. (Cl. 30—277)

The invention relates to new and useful improvements in dehorning chisels for use in dehorning cattle and is a substitute for Serial No. 443,428 filed May 18, 1942.

An object of my invention is to provide a dehorning chisel or instrument whereby the dehorning operation of young cattle, such as calves, goats and sheep, will be rendered more humane by the rapidity of the operation, thereby reducing attendant pain to the minimum and which dehorning operation by such improved chisel will permit the healing of the wound with a minimized tendency of infection or other undesirable complications which often result from sawing or shearing of horns of cattle of advanced age.

My improved dehorning instrument is adapted to sever the entire protruding knob-like cartilaginous horn structure of young cattle with a quick forcibly applied stroke of a slideable hammer member of the instrument against the chisel member which is held against the horn at the line of its junction with the scalp.

It is an object of my invention to provide a dehorning chisel which shall be simple in construction, comparatively low in cost of manufacture, and very simple and effective in use.

Another object of my invention is found in the provision of a dehorning instrument having a chisel of arcuate cross-section provided with side shoes preferably formed integrally with the chisel and extending outwardly from the sides of the chisel in a plane slightly above the bottom of the cutting edge of the chisel whereby such shoes through their slideable support on the scalp act as a safety guard to limit the depth of the cut in the event the operator causes the chisel to be unwarrantedly depressed too deeply into the top of the scalp during the dehorning operation.

A further object of my invention resides in the novel construction of the chisel which includes its formation, by die-stamping operation, from a sheet of metal plate into an arcuate shape with a plurality of cutting teeth formed in the medial portion of the cutting edge and with the upper side portions extending beyond the medial teeth in the form of pointed guides for guiding the movement of the chisel with the upper portion of the horn between such pointed guides.

Still another feature of my invention resides in slightly flattening the central portion of the toothed cutting medial portion and providing a sharpened cutting edge to extend the full length of the irregular peripheral end of the chisel.

With the above and other objects in view, my invention consists in the novel combination, con-

struction and arrangement of the members and parts shown in preferred embodiment in the attached drawing, described in the following specification, and particularly pointed out in the appended claims.

In the drawing, wherein like reference numerals indicate like or corresponding parts,

Fig. 1 is an illustration showing the operative position of a dehorning instrument embodying my invention;

Fig. 2 is a plan view of a dehorning chisel or dehorning instrument, with part in section, embodying my invention;

Fig. 3 is a side view of the instrument shown in Fig. 2 with the slideable hammer member moved into operative position;

Fig. 4 is a side view similar to that shown in Fig. 3 but showing the hammer member extended ready for movement into the horn-severing operation and with parts in longitudinal section to show construction details;

Fig. 5 is an enlarged longitudinal section of the chisel taken on line 5—5 of Fig. 2;

Fig. 6 is a cross-section taken on line 6—6 of Fig. 5;

Figs. 7 and 8 are side views of a slightly modified form of the hammer part of my improved instrument, Fig. 7 showing the hammer moved into operative position and Fig. 8 showing the hammer moved outwardly into position ready for striking movement;

Fig. 9 illustrates a modified chisel having a flattened arcuate cross-section; and

Fig. 10 is a cross-section similar to that shown in Fig. 6 but taken on line 10—10 of Fig. 9 and showing a modified form of safety shoe construction.

The dehorning instrument, as illustrated in Figs. 1 to 6 inclusive, consists of an intermediate tubular handle member 10 preferably made from a steel tube. A hammer member 11 is slideably mounted over the outer end of the tubular handle member 10. The hammer member 11 is formed from a solid round bar with a bored chamber 12 within the inner end to slideably receive therein the outer end of the tubular handle member 10. The hammer member 11 is preferably provided with a knurled-faced outer sleeve 13 as a grip for the operator's hand.

To prevent detachment of the hammer member 11 from the handle member 10, the handle member 10 is provided with a pair of diametrically opposed elongated slots 14 for the guide pin 15 which extends through the sleeved end of

the hammer member 11 and through the elongated slots 14.

The chisel 16 is preferably formed, as by die-stamping, from a single sheet of metal plate. The inner or rear end 17 of the chisel is of circular sleeve form to tightly embrace the outer end portion of the handle member 10 and the chisel 16 is secured to the handle member 10 in any suitable manner as by the rivet-headed pin 18 which extends transversely through the telescoped portions of the handle and chisel.

The operative end 19 of the chisel 16 is substantially of semi-circular cross-section and the medial cutting portion is provided with a plurality of cutting teeth 20. The side portions of the operative end 19 extend upwardly and forwardly and terminate beyond the medial toothed cutting portion in ends 21 which are preferably pointed as shown in the drawing.

I also prefer to provide the medial cutting portion with a centrally disposed flattened V-shaped portion 22.

The cutting end of the chisel is provided with a sharpened edge 23 extending through the entire peripheral edge of the outer end of the chisel.

As above stated, the chisel may be provided with a pair of side safety shoes 24 formed integrally with the chisel and in bent formation to extend downwardly from the upper portions of the chisel plate. As shown in Figs. 1 to 6 inclusive, the shoes 24 are formed by bending integral side portions 25 of the chisel plate downwardly over the outer side of the arcuate chisel portion and then bending the outer side portions laterally to form the pair of horizontally aligned shoes 24. The front end portions 26 of the shoes 24 are preferably curved upwardly to facilitate their sliding movement over the scalp in the event the operator unwarrantedly depressed the chisel too deeply into the top of the scalp. The bottom faces 32 of the shoes 24 are in actual practice only about one-eighth to three-sixteenths of an inch above the bottom face of the chisel.

The chisel may be formed of a flattened arcuate cross-section as shown in Figs. 9 and 10 and the safety shoes may be made in the form of laterally extended horizontally aligned, bent flanges 27 integral with the upper edges of the sides of the shoes.

Figs. 7 and 8 illustrate a modified form of my invention wherein the hammer member 28 consists of a solid round bar 29 having an enlarged head 30 adapted to forcibly engage with the outer end of the handle 10; the round shank 29 being slidably mounted in this type within the tubular handle 10 and secured against detachment therefrom by the cross pin 15 slidable within the elongated slots 14.

The instrument is shown in operative position in Fig. 1 with the chisel 16 applied against the side of one of the small horns 31. With the handle member 10 grasped in one hand and the hammer member 11 grasped in the other hand, the hammer member 11 is quickly forcibly brought into impact engagement with the end of the handle member 10 whereupon the chisel 16 will sever the horn 31.

It is obvious that various slight changes and modifications may readily be made in the details of construction by those skilled in the art upon perusal of the above specification and attached drawing without departing from the spirit of my invention defined in the appended claims.

I claim:

1. A dehorning instrument of the class described comprising an elongated handle, an elongated weighted hammer member in telescoped arrangement with one end of said elongated handle, means preventing detachment of said hammer member from said elongated handle but permitting movement of said hammer member relatively to said elongated handle, a chisel on the other end of said elongated handle, said chisel being of arcuate cross-section and having a sharpened toothed medial portion.

2. A dehorning instrument of the class described comprising an elongated handle, an elongated weighted hammer member in telescoped arrangement with one end of said elongated handle, said hammer member being movable relatively to said elongated handle, a chisel on the other end of said elongated handle, said chisel being of arcuate cross-section and having a sharpened toothed medial portion.

3. A dehorning instrument of the class described comprising an elongated tubular handle, an elongated hammer member of a solid section of metal having a tubular chamber in one end thereof for sliding movement therein of one end of said handle, said tubular handle having a pair of diametrically aligned elongated slots in its wall, a pin extending transversely through said hammer member and said slots preventing displacement of said hammer member from said handle but permitting movement of said hammer member relatively to said handle, and a chisel of arcuate cross-section mounted on the other end of said handle and having a sharpened medial cutting edge provided with a plurality of sharpened teeth.

4. A dehorning instrument as defined in claim 3 and including said chisel composed of separate die-stamped sheet metal including a formed tubular end connected to one end of said tubular handle, and means for securing the tubular end of said chisel to the handle.

5. A dehorning instrument of the class described comprising an elongated tubular handle, an elongated hammer member of a solid section of metal slidably mounted in one end of said tubular handle, said tubular handle having a pair of transversely aligned elongated slots, a pin extending transversely through said hammer member into said slots for preventing displacement of said hammer member from said handle but permitting movement of said hammer member relatively to said handle, said hammer member having a portion adapted for engagement with said handle, and a chisel of arcuate cross-section mounted on the other end of said handle and having a sharpened cutting edge provided with a plurality of teeth.

6. A dehorning instrument as defined in claim 5 and including said chisel composed of separate die-stamped sheet metal including a formed tubular end connected to one end of said tubular handle, and means for securing the tubular end of said chisel to the handle.

7. A dehorning instrument as defined in claim 5 and including said chisel composed of separate die-stamped sheet metal including a formed tubular end embracing one end of said tubular handle, and portions formed integrally with the upper edge portions of the opposite sides of the arcuate portion of said chisel bent to constitute a pair of laterally aligned flanges disposed slightly above the bottom of the toothed cutting edge to limit the depth of the cut.

8. A dehorning instrument as defined in claim

3 and including said chisel composed of separate die-stamped sheet metal including a formed tubular end connected to one end of said handle, and portions formed integrally with the upper edge portions of the opposite sides of the arcuate portion of said chisel bent to constitute a pair of transversely aligned longitudinal flanges disposed slightly above the bottom of the toothed cutting edge to limit the depth of the cut.

9. A dehorning instrument comprising a handle and a chisel on one end of said handle, said chisel having a substantially semi-circular body provided with a sharpened cutting edge, the medial portion of said cutting edge having a plurality of teeth.

10. A dehorning instrument comprising a handle and a chisel on one end of said handle, said chisel being formed from a metallic plate having one end secured to said handle and the free end thereof being of arcuate cross-section provided with a sharpened cutting edge, the medial portion of said cutting edge having a plurality of teeth and the side portions of said cutting edge extending upwardly and forwardly and terminating in pointed end portions disposed forwardly of said medial toothed portion.

11. A dehorning instrument comprising a handle and a chisel on one end of said handle, said chisel being formed from a metallic plate having one end secured to said handle and the free end thereof being of arcuate cross-section provided with a sharpened cutting edge, the medial por-

tion of said cutting edge having a plurality of teeth and the side portions of said cutting edge extending upwardly and forwardly and terminating in portions disposed forwardly of said medial toothed portion, and portions formed integrally with the upper edge portions of the opposite sides of said arcuate free-end bent downwardly and outwardly to constitute a pair of transversely aligned longitudinal flanges disposed slightly above the bottom of the medial portion of the cutting edge to limit the depth of the cut.

12. A dehorning instrument comprising a handle and a chisel on one end of said handle, said chisel being formed from a metallic plate having one end secured to said handle and the free end thereof being of arcuate cross-section provided with a sharpened cutting edge, the medial portion of said cutting edge having a plurality of teeth and the side portions of said cutting edge extending upwardly and forwardly and terminating in portions disposed forwardly of said medial toothed portion, portions formed integrally with the upper edge portions of the opposite sides of said arcuate free-end bent downwardly and outwardly to constitute a pair of transversely aligned longitudinal flanges disposed slightly above the bottom of the medial portion of the cutting edge to limit the depth of the cut, and said medial toothed portion having an inwardly converging flattened portion.

ALPHONS M. KUHL.
